UNITED STATES PATENT OFFICE

153,128

DESIGN FOR AN ARTIFICIAL LURE

Roy A. Ferris, Chicago, Ill.

Application June 24, 1946, Serial No. 130,955

Term of patent 3½ years

(Cl. D31—4)

To all whom it may concern:

Be it known that I, Roy A. Ferris, a citizen of the United States and a resident of Chicago, in the county of Cook and State of Illinois, have invented a new, original, and ornamental Design for an Artificial Lure, of which the following is a specification, reference being had to the accompanying drawing, forming a part thereof, and in which:

Fig. 1 is a perspective view of an artificial lure, showing my new design;

Fig. 2 is a front end elevational view of the same, and

Fig. 3 is a rear end elevational view of the same.

I claim:

The ornamental design for an artificial lure, as shown.

ROY A. FERRIS.
